PRESSURE RECORDING DEVICE

Guido V. D. Marx, Palo Alto, Calif., assignor to
Standard Oil Company of California, San
Francisco, Calif., a corporation of Delaware

Application September 16, 1931, Serial No. 563,043

4 Claims. (Cl. 234—5.3)

This invention relates to an apparatus for recording the pressures existing in well holes such as bores of oil, water or gas wells. The invention is particularly directed to a portable device capable of being lowered into a well hole and forming a record of the pressures existing at various depths in the well.

In the drilling of wells for the production of oil, water and gas, a hole is bored in the ground extending downwardly to a point or points where accumulations of hydrocarbons and/or water exist in the formation. It is frequently desirable to determine accurately at which points or depths gas, oil or other fluids enter the well hole and while much information is available from the examining of samples of the formation removed from the well while drilling, it has been found that much additional data of value can be obtained from a study of the pressures existing in a column of non-uniform density such as occurs in an oil or gas well. In addition to securing pressure information at or near points of actual fluid entry into the well hole, it will be appreciated by any one skilled in the art of oil production that by determining pressures at various points in a well hole, valuable information can be obtained regarding the ability of the formation to produce gas, oil or other fluids at various rates, the ultimate amount of such production recoverable by the well, the proper design of flow strings or tubing, and the efficient design and proper location of gas or air lift devices and pumps, or other mechanically operated devices for lifting fluids to the surface of the ground. For this reason, the device of this invention has been designed so as to be capable of obtaining a record of pressures existing throughout the entire column of the well under various conditions of flow ranging upward from a shut in or non-flowing condition.

40 Because of the particular use for which the pressure recording device of this invention is designed, numerous problems have been encountered. The apparatus must necessarily be simple, 45 accurate and sufficiently rugged to successfully withstand the shocks and jars incident to its travel from the surface downward through the well bore and its subsequent withdrawal from the well. The device must function satisfactorily when subjected to temperatures of about 250° F. 50 and pressures up to more than 3,000 pounds per square inch. The working parts must be sealed or protected from the entrance of oil, water, sand, gas, mud fluid, or other extraneous matter 55 which may be in the well. Furthermore, the

device should be capable of assembly and successful operation by non-technical operators, and the record should be clearly and permanently made.

Naturally, the device must be compact and of such size as to be readily portable, easily handled when inserting in a well, and capable of being lowered into a well through any customary flow string or tubing of customary diameter. The device, of course, must be sufficiently rugged so that in case the device is dropped into a well (as when the lowering cable or line should break), no undue damage is occasioned either the well, its equipment, or the instrument.

It is an object of this invention to disclose and provide a device for recording the pressures existing at various depths in a well bore in a simple and effective manner. 70

Another object is to disclose and provide a device for producing records of pressures within well holes, the device being capable of being lowered through flow string or tubing of any customary diameter. 75

Another object is to disclose and provide a device capable of being lowered into well holes and form a record of fluid pressures existing therein, the operating range of the device being readily alterable.

Another object of this invention is to disclose and provide a portable device capable of being lowered into well holes to form a record of pressures existing therein, the construction permitting ready and simple assembly and operation. 85

A still further object of this invention is to disclose and provide a construction of pressure recording devices adapted to be lowered into well holes whereby entry of mud fluid, oil, water, etc., into the device, is effectively prevented.

into the device, is effectively prevented. A still further object of the invention is to disclose and provide a device of simple and efficient construction capable of being lowered into well holes to form a permanent record of fluid pressures existing in such well hole at various depths. 95

These and other objects, uses and advantages of this invention will become apparent to those skilled in the art from the following detailed description of one preferred embodiment of this invention and its manner of operation, it being understood that the invention is not limited to the device specifically described hereinafter as those skilled in the art will readily observe that numerous changes and modifications and further simplifications could be made in the device. 100 105

In describing the invention, reference will be had to the appended drawings, in which 110

Fig. 1 is a general side elevation of the device being lowered into a well hole.

Fig. 2 is a longitudinal section through the upper portion of the device shown in Fig. 1.

5 Fig. 3 is a longitudinal section through the lower portion of the device shown in Fig. 1.

Fig. 4 is an enlarged longitudinal section through a portion of the device shown in Fig. 2.

10 Fig. 5 is an enlarged transverse section taken along the plane 5—5 indicated in Fig. 2.

Fig. 6 is a typical chart or record taken by the device from a flowing oil well.

15 As shown in Fig. 1, the device is preferably in the form of a cylinder provided with a lower section 1 forming a pressure chamber, an upper section 2 constituting a recording chamber, and an intermediate section 3 constituting a spring chamber. The device may be lowered through the tubing 4 or casing 5 of a well in any suitable manner, as by means of a line 6 attached to the upper portion of the device.

20 As stated hereinbefore, the device is adapted to form a record of the pressure existing within the well hole and one form of record is shown in Fig. 6. It will be seen that the ordinate represents pressures per pound per square inch whereas the abscissa represents time in minutes. The horizontal portion (a) of the record indicates that the record starts at zero pounds or atmospheric pressure. The sharp vertical line (b) of the graph was obtained when the instrument was placed in the well at the surface and indicates that the well was producing against a 250 pound back pressure at the time the record was made.

25 The horizontal line (c) then indicates a lapse of about 3 or 4 minutes before the device was lowered into the well. Subsequent horizontal lines in the record indicate points at which the lowering of the device was stopped in order to check the pressures at the depths indicated.

30 A maximum pressure of some 1710 pounds was registered at the bottom of the well (4500 feet) and the device was pulled back to the surface at a uniform rate and without further stops.

35 The pressure and time coordinates as well as the other descriptive matter appearing in Fig. 6, do not necessarily appear on the record as taken by the device. It will be observed that even at the slow lowering rate into the well the entire record consumed less than an hour.

40 Figs. 2 and 3 are longitudinal sections of one form of the device and represent respectively the upper and lower portions of the device shown in Fig. 1.

45 Referring to Fig. 3, a heavy steel tube 7 is threaded at either end to plugs 8 and 9, suitable gaskets being provided between the tube and the plugs to insure a tight closure. The lower plug 9 may be provided with an axial bore 10 adapted to slidably but snugly receive a piston 11 provided with an enlargement or stop 12 within the spring cylinder 7. The spring cylinder 7 is provided with a compression spring 13 resting against the stop 12 and yieldably urging the piston 11 into the pressure chamber 1, the latter being connected to the lower plug 9. The resistance to compression of the spring 13 is such that it is capable of movement within the ranges of pressure acting on the piston 11.

50 Surrounding the bore 10 in the plug 9 is a circular recess adapted to receive a gasket 14 having a U-shaped half section, the open end of the U facing the pressure chamber 1 and the inner surfaces of the gasket being in contact with the surfaces of the piston rod 11. The gasket 14 may

be retained by a metal washer 15 which in turn is held in place by means of a sleeve 16 threaded to the plug 9. The sleeve 16 surrounds the piston 11 but is spaced therefrom.

55 The exterior pressure chamber housing 1 may be provided with ports 17 adjacent the plug 9. Preferably the lower end of the pressure chamber 1 is filled with oil, water, or other incompressible fluid so as to present mud fluid, water, or other substances in the well hole from contaminating or contacting with the piston 11.

60 The gasket 14, because of its U-shaped half section, has been found to effectively prevent the entrance of oil or other liquid into the spring chamber 7 even when the device is subjected to high pressures. Manifestly, an increase of pressure within the pressure chamber 1 acting upon the gasket 14 will cause the gasket to more closely adhere to the piston 11. Even this construction, however, may permit a small amount of oil to enter the spring chamber 7 and for this reason an outlet 18 is provided in the lower portion of the spring chamber 7, said outlet being normally closed as by means of a threaded plug 19. Between runs, any oil which has entered the spring chamber 7 may be removed therefrom by opening the port 18.

65 Operably connected to the upper end of plug 8, as shown in Fig. 2, is a tubular housing 2 forming the recording chamber. The tubular housing 2 may be threaded to the plug 8 as indicated at 20, a copper gasket 21 being provided between the plug 8 and the cylindrical housing 2. The upper end of the cylindrical housing 2 may be closed by means of a plug 22. The plugs 8, 9 and 22 may be provided with drilled holes 23 which permit the use of a conventional spanner wrench in making up and disassembling the device.

70 As shown in Fig. 5, the upper end of the cylindrical housing 2 may be provided with two diametrically opposed longitudinal grooves 24 and 24' adapted to receive ears 25 extending from a plate 26 to which is attached a driving means such as a clockwork 27. The ears 25 rest on the bottom 120 of the longitudinal slots or grooves 24 and thus the clockwork or other driving means is suspended in the upper portion of the device. A bushing 28, provided with a square or hexagonal recess 29 in its center, is threaded to the upper end of the cylindrical housing 2 so as to press down against the plate 26 and retain said plate and the driving means 27 in position.

75 A diametral slot 30 is formed in the upper surface of the bushing 28, such slot being adapted to receive a locking bar 31, the locking bar being of such length as to enter into the slots or grooves 24 and 24' formed in the cylindrical housing 2, thereby preventing the bushing 28 from rotating and thereby loosening the driving means.

80 The driving means or clockwork 27 may be of any desired type. It may be a simple clockwork driven by one or preferably two main springs and provided with a gear train and escapement so that the recording drum (subsequently described) makes one revolution in 12 hours, 24 hours or any desired period of time; or the driving means may consist of a small electric motor and batteries.

85 A spindle 33 is attached to a stationary portion of the frame of the clockwork 27 by means of a self-aligning ball bearing 34. In this manner, an accurately centered and flexible support for the spindle 33 is provided.

90 Rotatably mounted upon the spindle 33 is a

recording drum of any suitable construction. As shown in the drawings however, the recording drum may consist of a brass tube 35 provided with flanged closure or hub members 36 and 37 at its ends. Suitable ball bearings 38 and 39 are provided between these hubs and the spindle 33 so that the drum 35 will revolve freely and independently of the spindle.

A spur gear 40 is attached to the upper hub 10 or end member 36 of the recording drum and a driving connection is then made between the spur gear 40 and the clockwork or other driving means 27. Such a driving connection is indicated by the pinion 41. A recording sheet may be wrapped 15 around the drum 35 and held in place by means of annular spring clamp members such as the member 42 at each end of the drum. Conventional chemical marking paper such as is used for engine indicators and the like, is suitable for this 20 service.

The lower end of the spindle 33 extends through an axial aperture formed in a flanged member 43 supported on the upper end of a cylindrical spacing member 44, attached in any suitable 25 manner, as by means of the flange 45, to the upper end of the plug 8. The spacing cylinder or member 44 is provided with a longitudinal slot, most clearly shown at 46 in Fig. 4.

Longitudinal motion of the piston 11 may be 30 transmitted to a stylus as by means of a rod 50 extending through the spring chamber 7 and through a bore 49 formed in the plug 8. The end of the rod 50 may extend into the recording chamber 2 as indicated in Fig. 2. The stylus, 35 consisting of a spring steel member 51 provided with a scribing point at its upper end, may be attached to an L-shaped bracket 52 carried by the upper end of the rod 50 between ball thrust bearings 53 and 54. These ball thrust bearings 40 are retained on the rod 50 between a nut 55 and a compression spring 56, said compression spring resting on a lock nut 57 carried by the rod 50, said lock nut being adapted to contact with the plug 8 and thus limit the downward motion 45 of the rod 50. By providing the ball thrust bearings 53 and 54 between the stylus bracket 52 and the rod 50, any rotation of the rod is not transmitted to the stylus bracket 52.

The stylus arm 51 as well as the end of the 50 stylus bracket 52, are guided in the longitudinal slot 46 of the spacer cylinder 44. In operation, therefore, the axial movement of the piston 11 is transmitted to the stylus 51 and recorded upon the cylinder 35 during the rotation of such cylinder.

It will be noted that the driving means 27 and the recording cylinder 35 are interconnected and may be removed as a unit through the upper portion of the recording chamber 2. Provision has 60 been made for automatically moving the stylus 51 out of cooperative or recording relation with the recording drum 35 when the driving means 27 or the recording drum 35 is moved longitudinally, as for example when removing the recording cylinder and clockwork from the recording chamber 2. These means may consist of a bell crank lever 60 pivotally connected to a threaded stud 61 carried by the lower side of the flanged cover plate 43 on the upper end of the spacing member 44. One end of the bell crank lever 60 is adapted to be depressed by the lower end of spindle 33 when the apparatus is assembled. The other end of the bell crank lever is pivotally connected to a push rod 62 extending through 70 suitable apertures in the cover plate and member

44 and on the same longitudinal center line as the slot 46 previously mentioned. A leaf spring 63 is carried by the spacer member 44 at a point diametrically opposite the slot 46 and is arranged to urge the plunger or push rod 62 outwardly against the stylus 51. It will be evident that when the plate 26, clockwork or driving means 27, spindle 33, and recording cylinder 35 are moved longitudinally out of the recording chamber 2, the leaf spring 63 will urge the plunger 62 against the stylus 51 and thus cause the stylus to move out of contact with the recording cylinder 35.

The device described hereinabove may be lowered into a well hole in any suitable manner. For example, the upper plug 22 may be provided with a threaded extension 64 which is hollow and which is provided with a through pin 65 to which a lifting cable or wire (not shown) may be attached. A piece of steel tubing 66 may be threaded over the outside of the extension 64 so as to serve as a means for a fishing tool to grasp if the device is lost at the bottom of a well.

It has been found that a product known as "1/2 inch, 7x7 wire center galvanized aircraft cord" 100 is suitable as a wire or lowering line. If the customary sand line is used, a swivel rope socket may be substituted for the pipe sleeve 66.

As will be seen from the description given hereinabove, the apparatus is essentially a spring 105 lever plunger which is acted upon by the pressure in the well to be tested. The motion of the plunger is transmitted to the stylus 51 and moves it longitudinally in direction proportion to the pressure on the plunger. The combination of the 110 longitudinal motion of the stylus and the rotary motion of the recording drum 35 gives a record on the sensitized paper similar to the record shown in Fig. 6 and this record may be compared with the data on the location of the instrument at any 115 particular time.

In order to obtain maximum deflection of the spring 13 with a corresponding maximum height of record on the sensitized paper carried by the recording drum 35, for various ranges of pressure, 120 it is desirable to provide sets of plugs 9 and pistons 11, the latter having various diameters. For example, in a recording device which is to operate under a maximum of 1000 pounds per square inch, a piston with a diameter of approximately 125 0.565 inches has been found suitable; a 3000 pound per square inch recorder has been found to require a piston of 0.326 inches in diameter when the same spring 13 is used. The diameter of the bore 10 and cup-leather 14 in the plug 9 must 130 correspond with the piston diameter.

The calibration of the instrument is preferably made with a conventional dead-weight tester such as is commonly used for the calibration of pressure gages. To use this device, all but one of 135 the ports 17 in the oil chamber 1 are plugged and the deadweight tester connected to the remaining port. It has been found that when a calibration is made in this manner and the pressure is increased to a maximum and then decreased to zero, two curves of deflection will be obtained. This is caused by the slight but unavoidable friction in the moving parts. In actual practice, however, when the device is dropped into a well at the end of a wire or cable, the jars and shocks which result from contact with the tubing joints will give a single curve or rather two curves which practically overlap. This actual curve will lie between the two found by calibration with the dead-weight tester.

To place the instrument in operation, plug 22, locking bar 31 and bushing 28 are removed. The clockwork 27, together with its appended recording cylinder 35, are then lifted out. A piece of sensitized paper is clipped to the recording drum 35 and the clock is wound and started. The recording unit is then replaced and the bushing 28, locking bar 31 and plug 22 reinserted. With the device in a vertical position, the oil or pressure chamber 1 is then filled with a clean lubricating oil to the level of the ports 17. This seals the space within the sleeve 16 and around the plunger 11 from gas, water, oil, sand, or mud fluid which will be forced into the chamber by external pressure when the device is lowered into the well.

A suitable wire or cable is then attached to the upper end of the device and the device lowered into the well, a record being made of the length of line played out whenever the descent of the instrument is stopped for a short period of time.

It is to be understood that although the device described hereinabove produces a record of all pressures encountered during the travel of the device into and out of the well, a similar arrangement of elements may be employed in producing a device which will record only the maximum pressure encountered by the device. If, for example, a driving mechanism 27 is not employed and a stationary and not rotating cylinder 35 is used, then the record obtained will merely indicate the maximum pressure encountered during the travel of the device into and out of the well.

Furthermore, those skilled in the art will observe that numerous changes and modifications could be made in the particular form of device shown in the drawings and all such changes and modifications as come within the scope of the appended claims are embraced thereby.

I claim:

40. 1. A portable device adapted to be lowered into well holes and form a record of fluid pressure therein comprising a cylindrical vessel provided with an axial piston extending therefrom and adapted to be acted upon by fluid pressure in a well hole, a spring in said cylindrical vessel adapted to yieldably urge the piston out of said vessel, a ported housing extending from said cylindrical vessel and surrounding said extended piston end adapted to receive and retain a body of liquid in contact with said piston end, a cylindrical housing operably connected to said cylindrical vessel and in alignment therewith, and a recording means

carried by said cylindrical housing and operably related to said piston for recording longitudinal motion of said piston.

2. A device adapted to be lowered into well holes and form a record of fluid pressure therein comprising a cylindrical hollow member, plugs adapted to close the ends of said member, an axial bore in the lower plug, a cylindrical piston slidably carried in said bore, a compression spring in said hollow member operably urging said piston out of said member, a sleeve in spaced relation to said piston extending from said plug, a housing enclosing said sleeve and piston and connected to said plug, ports in said housing near said plug, a liquid in said housing sealing said sleeve, a recording vessel connected to the upper plug, and a recording means carried by said recording vessel and operably related to said piston for recording the longitudinal motion of said piston.

3. A portable device adapted to be lowered into well holes and form a record of fluid pressures therein, comprising a cylindrical vessel provided with an axial piston extending therefrom and adapted to be acted upon by fluid pressure in a well hole, a spring in said cylindrical vessel adapted to yieldably urge the piston out of said vessel, a ported housing extending from said cylindrical vessel and surrounding said extended piston, means in said housing for sealing said piston from well fluid in the interior of said housing, a cylindrical housing operably connected to said cylindrical vessel and in alignment therewith, and a recording means carried by said cylindrical housing and operably related to said piston for recording longitudinal motion of said piston.

4. A device adapted to be lowered into well holes and form a record of fluid pressure therein, comprising a cylindrical hollow member, plugs adapted to close the ends of said member, an axial bore in one of said plugs, a cylindrical piston slidably carried in said bore, a spring in said hollow member operably urging said piston out of said member, a ported housing enclosing said plug, means in said housing for sealing said piston and said bore from well fluid in the interior of said housing, a recording vessel connected to the other of said plugs, and a recording means carried by said recording vessel and operably related to said piston for recording longitudinal motion of said piston.
